UNITED STATES PATENT OFFICE.

EDWARD ROBERTS, OF PHILADELPHIA, PENNSYLVANIA, ASSIGNOR TO CODE, HOPPER & GRATZ, OF SAME PLACE.

TIME-TELLTALE.

Specification of Letters Patent No. 31,853, dated March 26, 1861.

To all whom it may concern:

Be it known that I, EDWARD ROBERTS, of Philadelphia, Pennsylvania, have invented a Sentinel's Time-Check; and I do hereby declare the following to be a full, clear, and exact description of the same, reference being had to the accompanying drawing and to the letters of reference marked thereon.

My invention relates to improvements 10 fully described hereafter in that class of time checks or time registers in which is used a detachable graduated disk connected with and operated by the works of a clock or other time keeper.

15 The object of my improvement has been to produce a simple and efficacious instrument for checking or proving the alertness or remissness of a sentinel or watchman whose duty it is to mark the above mentioned 20 graduated disk at stated intervals during his hours of duty, so that it may serve as a permanent record of his attention or inattention.

In order to enable others skilled in the art to make and use my invention I will now 25 proceed to describe its construction and operation.

On reference to the accompanying drawing which forms a part of this specification, Figure 1 is a face view of my improvement 30 as applied to an ordinary eight day clock the door of the case being open. Fig. 2 is a vertical section of part of Fig. 1, Fig. 3 a view of the inside of the door as furnished with a marking device, Fig. 4 a vertical section 35 on the line 1 2 Fig. 3, Fig. 5 an inside view of the door as furnished with a modified marking device, Fig. 6 a vertical section on the line 3 4 Fig. 5 and Figs. 7 and 8 detached portions of the marking device shown in 40 Figs. 5 and 6. Figs. 1 and 2 represent the full size of the clock, Figs. 3, 4, 5 and 6 are drawn to a scale of one half of the full size, and Figs. 7 and 8 are drawn to a scale of double the actual size.

45 Similar letters refer to similar parts throughout the several views.

A represents the octangular case of an ordinary eight day clock having the usual works.

50 B is the door hinged to the case of the clock and consisting of a plain circular plate having two openings a and b which will be especially referred to hereafter, and a third opening c through which when the door is

closed a staple d on the case A passes, the 55 said staple being of a proper form to receive a suitable padlock, or the door may be furnished with any other appropriate locking apparatus.

C represents that spindle of the clock to 60 which the hour hand is usually attached, this spindle passing through and being secured to a plate D (Fig. 2) and being screwed on the end for the reception of a nut E between which and the plate D intervenes a disk or plate F of paste board or other suitable material, this disk consequently making one complete revolution in twelve hours. The disk may be graduated and numbered near the edge in the same 65 manner as the dial of an ordinary clock, in the present instance however it has marks representing the hours, and between these are intermediate marks representing the quarters of an hour. The opening a in the 70 door is so situated and is of such a form and extent that when the door is closed several of the marks on the disk are visible from the exterior, and the opening or slot b is so situated (supposing the door to be still 75 closed) that the sentinel or watchman can, by inserting the point of a pencil from the outside of the door into the slot, mark the disk on the space within the graduated edge of the same a radial line as shown in Fig. 1. 80

The key of the lock by means of which the door is secured is in the possession of the proper officer or superintendent of the building in which the instrument is situated the lock being beyond the control of 90 the sentinel whose instructions are to make or mark on the disk at stated intervals, say every half hour. Prior to the sentinel coming on duty the officer opens the door of the clock unscrews the nut E removes the disk, 95 which had been previously marked, from the spindle C and replaces it with an unmarked disk, taking care that at whatever hour the disk is attached the latter shall occupy such a position in respect to the pointed projection x of the opening a that the line on the disk representing the hour shall coincide with the said projection.

Now supposing the duties of the sentinel or watchman have to commence at eight 100 o'clock in the evening and to terminate at 6 o'clock in the morning and as before remarked that he has been instructed to mark

the disk once half an hour. If the sentinel commenced his rounds at the proper hour the mark 1 would be made on the disk at the point indicated in Fig. 1, that is to say 5 the mark would coincide with the line VIII on the graduated disk, and if he continued to attend to his duties properly he would make the marks 2 3. 4. 5. 6 &c. at the points indicated.

10 It will be observed that the opening *a* in the door is of such a width that one at least of the figures and a number of the adjacent marks on the graduated portion of the disk are visible at all times from the 15 exterior of the clock, and that the sentinel can at all times ascertain the proper time for marking the disk by watching when the hour and half hour lines on the graduated portion of the disk coincide with the pointed 20 projection *x*.

When the officer or superintendent arrives in the morning he unlocks the door and removes the disk and if he finds that the latter has been marked from a point opposite the 25 figure 8 to a point opposite the figure 6 at the proper intervals he is made aware of the fact that during his absence the sentinel has been on the alert and has punctually performed his duties from 8 o'clock in the 30 evening to six o'clock in the morning. Should the sentinel have been asleep or absent during the night the exact time during which he was off duty will be indicated by the absence of the proper marks or by their 35 irregularity, it will be seen therefore that this instrument affords a certain check or proof of due attention or any want of attention on the part of the sentinel or watchman, the disk bearing on its face a permanent record of any absence and the time 40 when such absence took place.

In some instances it may be necessary to place the instrument in such a position as to be beyond immediate access, in such cases 45 I attach to the door the device represented in Figs. 3 and 4.

G is a rod arranged to slide vertically in staples *f f* attached to the door B, a coiled spring *h* surrounding the rod and tending 50 to maintain the same in an elevated position. Near the top of this rod is a tube or sleeve *i* in which is fitted a sharpened pencil *j* the latter passing through a vertical slot in the door and bearing with its point against 55 the disk F. The whole is inclosed in a case H hinged to the door D and shown in Fig. 3 as being folded back. A cord or wire is attached to the lower end of the rod and extends to a point accessible by the 60 sentinel who pulls the wire at proper intervals thus drawing down the rod and making the required marks on the detachable disk the spring serving to raise the rod after it has been thus depressed.

65 When it is found inconvenient to apply

a new disk to the instrument every day the device illustrated in Figs. 5. 6. 7 and 8 may be used.

I is a vertical lever hung at *k* to the door B the back of this lever being furnished 70 with a spring *y* which bears against a hinged case H inclosing the lever, and tends to maintain the latter in the position shown in Fig. 6. The upper end of this lever has a vertical slot *m* seen in Figs. 7 and 8 and 75 through this passes a screwed pin *K* pointed at the end and secured by a nut *n* the head of this pin being provided with a projection arranged to fit into any one of the vertical row of orifices in the lever (see 80 Fig. 8). The pin is in the first instance so adjusted to the lever that its projection shall fit into the highest orifice of the row, and if the lower end of the lever has been pulled outward by the sentinel at intervals 85 throughout his hours of duty a circular row of indentations made by the pin will be found on the disk, these indentations occupying their proper position in respect to the marks on the graduated portion of the 90 disk, that is, providing the sentinel has been attending to his duties properly. Before he commences his next night's duty the pin is so adjusted that its projection on the head will fit into the hole next below that in 95 which it was previously inserted so that another circular row of indentations, within the first, will be made on the disk, and this adjustment from hole to hole may be continued from day to day so as to form any 100 desired number of circular rows of indentations in the disk each row indicating one night's alertness or inattention on the part of the sentinel. There may be six holes in the lever, for instance, the pin being ad- 105 justed to the highest hole on Monday the next on Tuesday, and so on, so that when the disk is removed after the sixth night the outer circular row of indentations will point out the attention or inattention of the 110 sentinel on Monday night the next row his punctuality or want of punctuality on Tues- 115 day night and so on. If, during any half hour of any night of the six the sentinel has been asleep or off duty, not only the night but the exact time of the night when the neglect took place is discovered by examining the several rows of indentations.

I wish it to be understood that I do not claim broadly a detachable graduated disk 120 applied to a clock or time keeper and inclosed within the case of the same, such a device being shown in the English patent No. 957 of 1852: but

I claim as my invention, and desire to 125 secure by Letters Patent—

1. The detachable graduated disk F, applied to the works of the clock, substantially as herein set forth, in combination with the lid B, its openings *b* and *a*, and the pointer 130

x, or its equivalent when the said openings, and pointer, are arranged in respect to each other and to the disk as and for the purpose herein described.

5 2. The spring lever I, with its adjustable pin K, in combination with the detachable graduated disk, and the lid B, and its openings *b* and *a*.

In testimony whereof, I have signed my name to this specification, in the presence of 10 two subscribing witnesses.

EDWARD ROBERTS.
